UNITED STATES PATENT OFFICE

OTHO C. DURYEA, OF WATERBURY, CONNECTICUT, ASSIGNEE TO O. C. DURYEA CORPORATION, OF WILMINGTON, DELAWARE, A CORPORATION OF DELAWARE

CAR CONSTRUCTION

Application filed January 29, 1926. Serial No. 84,737.

This invention relates to railway rolling stock, and more particularly to a railway car structure wherein a "long travel" longitudinal member is adapted for movement relative to the remainder of the structure, in combination with means for yieldingly resisting said movement, whereby the shocks and impact stresses incident to operating conditions are prevented from damaging the car or its lading.

In my co-pending application Serial No. 26,267, filed April 27, 1925, Patent No. 1,693,194, November 27, 1928, there is disclosed a railway car structure including a plurality of transverse members, such as bolsters, in combination with a long travel center member, adapted for longitudinal movement relative to said bolsters, and means including resilient and friction elements of relatively long travel for resisting said relative movement.

An object of the present invention is to provide novel means of relatively long travel for absorbing the shocks imparted to a car under operating conditions.

Another object of this invention is to provide a car structure of the above type wherein the resilient elements of long travel are interposed between the bolster or bolsters and the adjacent end sill or sills of the car.

A further object is to provide novel shock absorbing means of long travel in combination with friction means whereby a portion of the energy imparted to the car is dissipated.

A further object is to provide novel resilient means of long travel for resisting longitudinal movement between the center member and the car bolsters, which means are interposed between the coupler means and the bolster, and which extend from the coupler means to the bolster.

A further object is to provide novel means for yieldingly resisting relative movement between the center member and the remainder of the car structure in combination with means for preventing the resilient means from going solid.

Another object is to provide a novel car structure of the above type which embodies

friction means for resisting relative movement of the center member, the resistance offered by said means being adapted to vary in proportion to the weight of the lading.

Another object of this invention is to provide novel shock absorbing means of relatively long travel in combination with means for providing train slack.

A still further object is to provide novel means for securing a predetermined and an invariable amount of train slack.

Another object is to provide novel means for maintaining the resilient members in operative position relative to the bolster and center member.

Another object is to provide a novel underframe structure including novel cross-bearers and bolsters.

Additional objects are to provide a car structure of the above type which is adapted for ready assembly, which is rugged, and which is relatively inexpensive to manufacture. These and other objects will appear more fully hereinafter.

The invention will be readily understood by reference to the accompanying drawings illustrating two embodiments of the present invention. It is to be expressly understood, however, that these drawings are for the purposes of illustration only and are not designed as a definition of the limits of the invention, reference being had to the appended claims for this purpose.

In the drawings, wherein like reference characters refer to like parts throughout the several views.

Fig. 1 is a top plain view, with parts broken away, illustrating one type of long travel means which may be employed for yieldingly resisting relative movement between the long travel center member and the remainder of the car structure, in accordance with the present invention;

Fig. 2 is a transverse sectional view taken on the line 2-2 of Fig. 1;

Fig. 3 is a longitudinal sectional side view taken on the line 3-3 of Fig. 1;

Figs. 4 and 5 are sectional views taken on the lines 4-4 and 5-5 respectively, of Fig. 3;

Fig. 6 is a top plan view in section taken on the line 6—6 of Fig. 3;

Fig. 7 is a transverse section taken on the line 7—7 of Fig. 6;

5 Fig. 8 is a longitudinal sectional view illustrating a second embodiment of the present invention;

10 Figs. 9 and 10 are transverse sections taken on the lines 9—9 and 10—10 respectively, of Fig. 8;

Fig. 11 is a detail top plan view illustrating certain novel features of the underframe which may be provided in accordance with the present invention;

15 Fig. 12 is a transverse section on the line 12—12 of Fig. 11; and

20 Figs. 13, 14 and 15, are detail sectional views illustrating three different types of friction means which may be embodied in the car structure constituting the subject matter 25 of the present invention.

Referring to Figs. 1 to 7 inclusive, the car structure constituting the subject matter of the present invention includes a pair of novel body bolsters which are adapted to be mounted on truck bolsters and trucks (not shown) in a suitable manner well understood in the art. Only one body bolster 11 is shown in the drawings but it is to be understood that a 30 body bolster is employed at each end of the car as is now the general practice. In order to employ a large scale for the drawings only one end of the car structure is illustrated. Secured in any suitable manner, as by means 35 of rivets, to the opposite ends of the bolster 11, are side sills 12 and the latter are joined at their extremities by the usual end sill 13.

In order to give the underframe and body 40 structure sufficient rigidity and to prevent the same from being thrown out of line, a pair of diagonal braces 14 are preferably riveted at one end to the end sill 13 and at the opposite end to the outer portions of the bolster 11. Extending through suitable openings 45 (Fig. 7) in the bolster 11 is a long travel center member which, in the form shown, extends from end to end of the car and is constituted by channels 16 that are rigidly maintained in spaced relation by means of suitable tie plates 17. Preferably these tie plates, which 50 may be constituted by channel members, are secured between the channels 16 with the web of each tie plate substantially flush with the upper or lower flanges of the channel members constituting the center member (Fig. 11).

In order that forces imparted to the car 60 structure may be gradually and yieldingly resisted, thereby avoiding damage to the car structure or lading, the center member is adapted for longitudinal movement relative to the bolsters, which movement is of relatively great extent, and means are provided for yieldingly resisting relative movement 65 of the center member. If desired, said means

may include means for dissipating a portion of the energy tending to produce said relative movement. In the form shown, resilient members 18 and 19, which may be of any suitable type, together with friction means to be described more fully hereinafter, yieldingly resist relative movement of the center member. Preferably the bolsters are provided on their outer faces with recesses 20 and in each of said recesses is positioned a follower plate 21 (Fig. 3) which has engagement on one face thereof with an inner wall of the recess and on its opposite face with the resilient members 18 and 19, the member 19 in the form shown being disposed within the resilient member 18 and concentric therewith. Suitably secured, as by rivets, to the lower surface of the end sill 13 and centrally thereof, is a striking plate guide 22 provided with jaws 23 which engage the upper flanges of the channel members 16 and slidably support the latter. If desired, the striking plate guide 22 may also be riveted to the diagonal bracing members 14, as indicated at 24 in Fig. 1. As shown in Figs. 3 and 4, a striking plate 25 is secured to the channel members 16 at the ends of the latter, and preferably the outer end of said striking plate extends beyond the outer ends of said channel members, as is indicated at 25a, Fig. 6. The rear end of the striking plate 25 extends inwardly for the greater part of the length of the striking plate guide 22 and is slidably supported by the latter. In engagement with the face of the inner end of the striking plate, which end constitutes a transverse beam, is a follower 26 which is engaged on its opposite face by the resilient member 18. Preferably a sleeve 27 extends through a central opening in the follower 26 and the striking plate 25 into engagement with the face of the inner end of a coupler shank 28a provided with a coupler head 28 of the usual type. As shown, the inner end of the sleeve 27 is provided with a flanged portion 27a which is of greater diameter than the openings in the follower plate 26 and striking plate 25 and in engagement with said flange is the outer end of the resilient member 19.

Means are provided for preventing the resilient members 18 and 19 from moving the follower plate 26 from its normal position toward the adjacent end of the car. In the form shown, said means are constituted by the striking plate guide 22, which has engagement with the upper portion of said follower 26, and by a transverse plate 31 which engages the lower portion of said follower. One or more hanger irons 29, which are preferably constituted by metal straps, are riveted as at 30 (Fig. 4) to the side flanges of the striking plate guide 22 and at the opposite ends thereof said hanger irons are riveted to said transverse plate 31 which

is suitably strengthened at the center thereof, as by means of ribs 31a, and which is normally in engagement on its inner face with the follower plate 26. Longitudinal movement of member 31 may be prevented by tension members 32, which are secured, as by means of rivets, to said transverse member 31 at their outer ends, and which extend rearwardly and are suitably secured by bolts 10 or rivets to laterally projecting lugs 33 which may be formed integrally with the bolster 11.

The coupler shank 28a is slidably secured, as by means of a key 34, to the striking plate and channel members 16, which key extends through registering openings 35 in said striking plate and channel members. The openings 35 are of greater width than the width of the key, as is the usual practice.

Suitable means are provided on the center member for imparting motion to the follower plate 21 to compress resilient members 18 and 19 when said center member moves in one direction, the follower 21 being held against movement in the opposite direction by engagement with the bolster 11. In the form shown, said means are constituted by a suitable number of lugs or fingers 36 (Figs. 1, 6 and 7) which extend inwardly through an opening or openings 37 in the channel members 16, and which are preferably formed integrally with plates 38 which are secured as by means of rivets to the outer faces of the webs of the channel members 16. Normally the lugs 36 are in abutting engagement with the inner face of the follower plate 21 and said lugs may move relative to the bolster 11 in openings 39 provided in the latter.

Means are preferably provided for preventing the resilient members 18 and 19 from going solid. To this end angle brackets 49, constituting stops, are secured to the outer faces of the webs of the channel members 16 at a suitable distance from the outer face 45 of the bolster 11. If desired, the stops for limiting the movement of the center member relative to the bolster in the opposite direction, may be constituted by lugs 41 which are integrally formed with the plates 38.

Operation.—It will be understood that preferably the yielding means, including the follower plates and the members cooperating therewith, as well as the stops, are provided at each end of the car. If a buffing force is applied to the coupler 28 the coupler shank 28a, key 34, and sleeve 27, are moved to the left relative to the remaining elements of the car structure, against the tension of resilient member 19, the opposite end of said resilient member being held against movement by the follower plate 21 in abutting engagement with the bolster 11. If the buffing force is sufficiently great, resilient member 19 is compressed and the inner end of the coupler shank 28a moves into engagement with the

wall of the recess 25b provided in the striking plate 25 and simultaneously the inner edge of the key 34 engages the inner walls of the openings 35 in the channel members 16 and the striking plate 25, whereupon longitudinal movement, relative to the bolster 11, is imparted to the center member. Since the striking plate 25 is rigidly secured to the center member, said striking plate together with the follower plate 26 and sleeve 27 are forced to the left as viewed in Fig. 3, compressing the outer resilient member 18 and further compressing resilient member 19. The relative movement of the center member is therefore yieldingly resisted by both the resilient members 18 and 19. If the buffing force is sufficiently great, stops 40 may be moved into engagement with the outer face of the bolster 11 and said stops are so positioned relative to said bolster as to prevent either of the resilient members 18 or 19 from going solid.

Movement of the center member relative to the bolster 11 is also yieldingly resisted by the resilient means provided adjacent the bolster at the opposite end of the car since movement of said center member imparts movement to lugs or fingers 36 provided adjacent the bolster at the opposite end of the car (not shown) which motion is transmitted to a follower plate 21 to compress resilient members 18 and 19. The opposite ends of the resilient members at this time are held against movement by engagement of sleeve 27 and follower plate 26 with the striking plate guide 22 and the transverse member 31. If the relative movement of the center member is sufficiently great to cause the stops 40 to contact with the bolster 11, the stops 41 at the opposite end of the car simultaneously contact with the adjacent bolster and any oversolid blow is thus equally distributed between the opposite ends of the car.

If the coupler 28 is subjected to draft, i. e., if a force is imparted to the coupler 28 tending to move it to the right as viewed in Fig. 3, this force is transmitted by key 34 to the center member and if sufficiently great the center member is moved to the right relative to the bolster 11, carrying with it the lugs 36. As set forth above, movement of the lugs 36 forces the follower 21 out of engagement with the bolster 11 and the resilient members 18 and 19 are compressed since the opposite ends of the same are held against movement by engagement of sleeve 27 with follower plate 26, which latter in turn is held against movement by the striking plate guide 22 and the transverse member 31.

It will be apparent that the resilient members are adapted to yieldingly resist relative movement of the center member in either direction and that the resilient members at the opposite end of the car coact in resisting said movement. Due to the relatively long travel of the center member the enormous forces

imparted to the car are effectively resisted without damage to the car structure or its lading and it will be understood that this relative movement is several times greater than the movement of the usual draft mechanism now employed. For example, said movement may be as great as six inches, eight inches, or even more.

Referring to the embodiment of the invention illustrated in Figs. 8 to 10 inclusive, relative movement of the follower plate 42, adjacent the striking plate and coupler, to the right as viewed in Fig. 8, is prevented by means of a suitable number of bolts or rods 43 which extend through openings in said follower plate and in the bolster 44, said bolts or rods 43 being maintained in operative position by means of nuts 45. Rods 43 and nuts 45 constitute a yoke for the resilient members. In this embodiment therefore the follower plate 42 does not have engagement with the striking plate guide 46. In other respects, however, this embodiment is substantially the same as the first embodiment described above and a detailed description of the operation of the same is considered unnecessary.

In certain types of cars it may be desired to dissipate a portion of the forces imparted to the car. Accordingly, means may be provided for dissipating a portion of the energy tending to produce relative movement between the center member and the bolsters. Various means may be employed for this purpose, in combination with the resilient members heretofore described. For example, longitudinal wooden stringers 47 (Fig. 13) may be interposed between the bottom of the car flooring 48 and the upper flanges 40 of the channel members 16. Preferably these stringers are bolted to the flooring and extend between the cross-bearers. Since the coefficient of friction of wood on metal is substantially 0.4, a predetermined amount of friction can be provided, in addition to the resilient members, for yieldingly resisting relative movement of the center member. A portion of the weight of the lading is directly transmitted by the stringers to the center member whereby the friction generated between the stringers and the center sill will vary in proportion to the weight of the lading in the car.

If desired, a Z-bar 49 (Fig. 14) may be suitably secured to the floor in the vertical plane of the channel members 16 with its lower flange in engagement with the upper flange of said members 16. In this instance the friction will be less than that provided by the wooden stringers since the coefficient of friction of metal on metal is substantially 0.27. However, as pointed out above, this friction will vary with the weight of the lading.

If desirable, a greater amount of friction

may be provided between the center member and the remainder of the car structure than can be secured by the use of either of the means described above. For example, a T-bar 50 (Fig. 15) provided with an inverted V-shaped notch in the shank thereof, may be secured at its flanges to the under surface of the car flooring in the vertical plane of the channel members 16. In engagement with the notched portion of said bars 50 are longitudinally disposed T-bars 51 which may be secured, as by means of rivets (not shown), to the upper flanges of the members 16, the shank of the T being provided with a wedge-shaped portion 51a which extends into the groove of the bars 50. The bars 51 should be of such length as to terminate a distance short of the bolster 11, or a cross-bearer 52, which is not less than the distance normally between the stops 40 or 41, and the adjacent faces of the bolster 11, in order that said bars do not interfere with the relative movement of the center member. The friction between bars 50 and 51 may be varied within wide limits by changing the angles of the wedge-shaped portions 51a and the grooves in the members 50.

Transverse supporting members are provided at suitable points intermediate the bolsters 11. As shown, these transverse members or cross-bearers 52 are constituted by pressed or stamped plates having integrally formed peripheral flanges 53, and constitute combined compression and tension members. Since, in the form shown, the cross-bearers 100 form the intermediate load carrying members, the upper portion of each cross-bearer constitutes a compression member and the lower portion of the same constitutes a tension member, it being understood that said cross-bearers are rigidly attached at the opposite ends of the same to the side sills 12. However, if the center member is so constructed as to constitute the primary load carrying member the upper portions of the cross-bearers would constitute tension members. An opening 54 is provided in the central portion of each of the cross-bearers whereby the center member constituted by the channel 16 may have longitudinal movement relative thereto.

Means are provided for preventing shear stresses from disrupting the cross-bearer and for providing bearing surfaces for the center member. In the form shown, a center brace 120 55, which is preferably formed as a casting, is securely bolted or riveted to the lateral face of the cross-bearer opposite to the face from which extends the flange 56 surrounding the opening 54. The center brace 55 may be provided with suitable strengthening ribs 57 and, adjacent the top and bottom thereof, with integrally formed and laterally extending ears 58 which engage the upper and lower faces of the flanges of the channel members 125.

16. In the form shown, the ears 58 are L-shaped to provide a relatively large supporting surface at each cross-bearer for the channel members 16.

5 Preferably means are provided for preventing longitudinal movement from being imparted to the cross-bearers because of the frictional engagement therewith of the relatively movable center member. In the form 10 shown, an angle bar 59 is provided for this purpose. Preferably one end of this angle bar is rigidly attached by means of bolts or rivets to a lug 60 which extends laterally from the inner face of the bolster 11 and 15 intermediate its ends said bar is suitably secured to each of the cross-bearer center braces 55 by rivets having engagement with downwardly extending ears 61 that are preferably formed integral with said center braces. If 20 desired, the opposite end of the angle iron 59 may be rigidly attached to the bolster at the opposite end of the car (not shown) but preferably said angle iron is attached to only one bolster.

25 It will thus be perceived that there is provided a car construction wherein the forces imparted to the same are yieldingly resisted by means having relatively long travel, and yet one which is so constructed that a predetermined amount of train slack is provided 30 for. The resilient members employed for resisting the relative movement are interposed between the bolsters and the adjacent end sills of the car. A portion of the energy imparted 35 to the car may be dissipated by friction means and the amount of friction available for dissipating such energy varies with the weight of the lading carried by the car. One of the resilient members employed at each 40 end of the car is adapted to coact with the coupler mechanism associated therewith for providing an invariable amount of train slack. Said resilient members also coact with the other resilient members for yieldingly resisting relative movement of the center member. Permanent setting of the resilient members is avoided since suitable stops are provided for preventing said members from going 45 solid. Means are associated with the resilient members whereby each member yieldingly resists relative movement of the center member in either direction.

The distance between the body bolsters and the adjacent ends of a car cannot be varied 50 within wide limits for reasons well understood in the art. In standard cars the distance between the bolster and the adjacent end sill is usually from 4½ to 5 feet. The distance between the inner end of the coupler 55 shank and the bolster is therefore quite limited. The present invention is broadly directed to long travel means positioned in the limited space between the bolster and the coupler means for yieldingly resisting longitudinal 60 movement of the center member. Heretofore

draft gears of very limited travel have been interposed in this limited space but so far as is known the maximum travel of draft gears is approximately $3\frac{1}{16}$ inches while the travel recommended by the American Railway Association is only $2\frac{3}{4}$ inches. Stated otherwise, the draft gear of modern cars, due to the center sill construction among other reasons, must be mounted in the "extremely small space of $2\frac{1}{8}$ inches by $12\frac{7}{8}$ inches by 75 9 inches". The present invention secures long travel and at the same time provides for the desired amount of train slack.

While two embodiments of the invention have been illustrated and described with considerable particularity, it is to be expressly understood that the invention is not limited thereto since various changes may be made in the structures without departing from the present invention. For example, the resilient members may be positioned between the bolsters and the adjacent cross-bearers instead of between the bolster and the adjacent end sills. If this is desired yielding 80 coupler means of the type disclosed in my co-pending application Serial No. 26,267, filed April 27, 1925, or the means disclosed in my co-pending application Serial No. 79,449, filed January 5, 1926, may be employed for overcoming the inertia of the 85 center member and for providing train slack. Diagonal members may be employed for strengthening the cross-bearers against longitudinal bending movement, as disclosed in my co-pending application Serial No. 27,041, filed April 30, 1925, in which event it may be unnecessary to secure the angle iron 59 to one of the bolsters. Reference is therefore 90 to be had to the appended claims for a definition of the limits of the invention.

What is claimed is:

1. In a railway car comprising a body structure including a bolster, a long travel center member mounted for movement relative to said bolster, coupler means operatively secured to said center member including a coupler of the standard type, and resilient means extending from a point adjacent the inner end of the shank of said coupler to said bolster for yieldingly resisting said relative movement, said coupler being adapted for movement of limited extent relative to the center member whereby the train slack is independent of the travel of the 100 resilient means.

2. A railway car comprising a plurality of transverse members including a bolster, a long travel center member extending substantially the length of the car and mounted for longitudinal movement relative to said bolster, coupler means operatively connected to said center member, and means including a plurality of resilient members extending from a point adjacent the inner end of the 105 coupler shank of said coupler means to said 110 115 120 125 130

bolster for resisting said relative movement.

3. In a railway car comprising a plurality of transverse members including a bolster, a longitudinal member mounted for movement relative to said bolster, coupler means including a coupler of the standard type and a key for movably connecting the coupler to the end of the longitudinal member and long travel means including two concentrically arranged coil springs extending from the bolster to a point closely adjacent the inner end of the shank of said coupler for resisting said relative movement one of said springs being disposed within the other.

15 4. In a railway car comprising a plurality of relatively movable parts including a bolster and a center member, said bolster having a recess therein, a coupler of the standard type, a key for movably securing the coupler to the end of said center member, and means including a pair of coil springs extending from a point adjacent the inner end of the shank of said coupler inwardly within said recess for yieldingly resisting said relative movement in both directions, one of said springs being of greater length than the other and the shorter of said springs being adapted to yieldingly resist movement of the coupler relative to the center member.

25 5. A railway car comprising a plurality of transverse members including a bolster having a recess therein, a longitudinal member extending substantially the length of the car and mounted for movement relative to said bolster, coupler means including a coupler secured to said member, said coupler having limited movement relative to the member, and resilient means for resisting said relative movement, a portion of said resilient means extending into said recess and the opposite end of said means extending to a point adjacent the inner end of the shank of said coupler.

45 6. In a railway car structure comprising a bolster, a center draft member mounted for longitudinal movement relative to the bolster, a follower plate normally having engagement with said bolster, a striking plate carried by the center member, guiding means for the striking plate carried by the structure, a coupler having operative engagement with the striking plate and center member, means carried by said center member for engaging said follower plate, and yielding means having engagement with the follower plate and said striking plate and guiding means for resisting said relative movement.

7. In a car structure including a bolster having a recess therein, a center member mounted for movement relative to said bolster, a follower in said recess, lugs on said center member adapted for engagement with said follower, resilient means having engagement at one end thereof with said follower, a

coupler secured to the center member, a follower having engagement with said coupler and the opposite end of said resilient means, and stops for said last named follower carried by the car structure.

8. In a railway car structure comprising a plurality of transverse members including a bolster, a center member extending substantially the length of the structure and mounted for movement relative to said bolster, yielding means including a resilient member having operative engagement at one end thereof with said bolster for resisting said relative movement, a coupler secured to said center member, and a sleeve engaging said coupler and the opposite end of said resilient member.

9. In a railway car structure comprising a plurality of transverse members including a bolster, a center member mounted for movement relative to said bolster, a coupler having head and shank portions, a key for movably securing the shank of the coupler to said center member, and means for yieldingly resisting said relative movement, said means including a resilient member operatively associated with the shank of said coupler and adapted to yield on buffing shocks to yieldingly resist movement of the coupler relative to the center member and to further yield to resist movement of the center member relative to said bolster.

10. In a railway car structure comprising a plurality of transverse members including a bolster, a center member mounted for movement relative to said bolster, coupler means operatively secured to said center member including a coupler, a key for movably connecting the coupler to the center member, and resilient means interposed between the coupler and bolster for resisting movement of the coupler relative to the center member, and other resilient means extending from a point adjacent the shank of the coupler of said coupler means to said bolster to cooperate with said first named resilient means for yieldingly resisting movement of the center member relative to the bolster.

11. In a railway car structure comprising a plurality of transverse members including a bolster, a center member mounted for movement relative to said bolster, a coupler movably connected to said center member, yielding means having operative engagement with the inner end of the shank of said coupler and bolster for resisting movement of the coupler relative to the center member, and other yielding means cooperating with said first mentioned yielding means for resisting movement of the center member relative to said bolster.

12. In a railway car structure including a bolster, a center member extending the length of said structure and mounted for movement relative to said bolster, coupler

- means operatively secured to said center member, a resilient member interposed between the coupler means and bolster and having operative engagement at its opposite ends with the bolster and the inner end of the coupler shank of said coupler means for resisting movement of the coupler shank relative to said center member, and other resilient means surrounding said resilient member and adapted to coact therewith for yieldingly resisting movement of the center member relative to said bolster.
13. A railway car structure comprising a plurality of transverse members including a bolster, a center member mounted for longitudinal movement relative to said bolster, a coupler operatively secured to the center member, resilient means extending from the bolster to a point adjacent the shank of said coupler for resisting said relative movement, and friction means having operative engagement with the center member for dissipating a portion of the energy tending to produce said relative movement.
14. A railway car structure including a bolster having an opening therethrough, a member extending through said opening and adapted for movement relative to said bolster, a coupler operatively secured to said member, resilient means extending from a point adjacent the inner end of the shank of the coupler to said bolster for yieldingly resisting said relative movement, and means having frictional engagement with said member for dissipating a portion of the energy tending to produce said relative movement.
15. A railway car comprising a body structure including a bolster, a center member mounted for movement relative to said bolster, coupler means carried by the center member, resilient means extending from the coupler means to said bolster for yieldingly resisting said relative movement, and friction means for dissipating a portion of the energy tending to produce relative movement, the friction generated by said means varying with the lading carried by said structure.
16. A railway car structure comprising, in combination, a plurality of bolsters having openings therethrough, side sills secured to said bolsters, end sills secured to the side sills, one or more transverse members intermediate said bolsters and secured to said side sills, said transverse members having openings therein, center braces secured to said transverse members adjacent said openings, a center member extending through the openings in said transverse members and bolsters and mounted for movement relative thereto, couplers movably connected to the opposite ends of the center member, means for resisting movement of the center member relative to said bolsters, and means for connecting said center braces to one of said bolsters.
17. In a railway car comprising a body structure including a bolster and a striking plate guide, a center member mounted for movement relative to said bolster and guide, resilient means for resisting said relative movement, couplers movably connected to said center member, a follower interposed between said resilient means and said guide and normally having engagement with the latter, a member normally having engagement with said follower and adapted to coact with said striking plate guide to prevent movement of the follower in one direction, and tension members for securing said last-named member to said bolster.
18. In a railway car structure having relatively movable parts and including a long travel draft member and a frame, resilient means for yieldingly resisting said relative movement, a follower having engagement with said resilient means, a member for preventing movement of said follower in one direction, hanger irons secured to said frame for maintaining said member against movement in a vertical plane, and tension members for resisting movement of said member in a horizontal plane.
19. A railway car structure comprising a bolster having an opening therethrough, cross-bearers having openings therethrough associated with said bolster, a center member extending through the openings in said bolster and cross-bearers and adapted for movement relative to the bolster and cross-bearers, coupler means including a coupler operatively secured to said center member, said coupler being adapted for limited movement relative to said center member, and long travel resilient means interposed between said bolster and said coupler means for yieldingly resisting relative movement of the center member and also resisting movement of a coupler relative to said center member.
20. A railway car structure comprising a bolster, a center member mounted for movement relative to said bolster, coupler means secured to said center member and adapted for limited movement relative thereto, a resilient member associated with the coupler means, and resilient means for resisting the relative movement of the center member, said resilient member being adapted to resist movement of the coupler means relative to the center member and to further resist movement of the coupler means when the latter moves with the center member.
21. A railway car structure comprising a bolster, a center member mounted for longitudinal movement relative to said bolster, resilient means for resisting the movement of said member, coupler means carried by said center member and adapted for limited movement relative to said center member, resilient means for resisting the movement

of the coupler means relative to the center member and for resisting movement of the coupler means with the center member.

22. A car structure comprising transverse members including a bolster, a longitudinal member mounted for movement relative to said bolster, means for yieldingly resisting said relative movement, coupler means carried by said longitudinal member, said coupler means being adapted for movement relative to the longitudinal member, and means for yieldingly resisting movement of the coupler means relative to the longitudinal member, said last-named means being adapted to resist movement of the coupler means with the longitudinal member.

23. A car structure comprising bolsters, a long travel center draft member mounted for movement relative to said bolsters, cross-bearers intermediate the bolsters for guiding said member, the latter having sliding engagement with the cross-bearers, ears projecting from said cross-bearers, means secured to said ears and one of said bolsters for preventing movement of the center member from deflecting said cross bearers, and yielding means for resisting relative movement of the center member.

24. A railway car comprising a body structure including a bolster, a center member mounted for movement relative to said bolster, coupler means including a coupler provided with a shank operatively secured to said center member, and resilient means extending from a point adjacent the inner end of the shank of said coupler to said bolster for yieldingly resisting relative movement of the center member and bolster, and for yieldingly resisting movement of the coupler relative to the center member.

25. A railway car comprising a body structure including a bolster, a center member extending substantially the length of the structure and mounted for movement relative to said bolster, coupler means carried by the center member, resilient means extending from the coupler means to said bolster for yieldingly resisting said relative movement, said resilient means being mounted in the horizontal plane of the coupler means, and friction means for dissipating a portion of the energy tending to produce relative movement, the friction generated by said means varying with the loading carried by said structure.

26. In a car structure of the type embodying a long travel draft member extending substantially the length of the structure, a coupler, means for movably securing the coupler to the center member, resilient means for resisting relative movement of the center member and coupler in one direction, said center draft member being adapted for long travel movement relative to the car body and

a striking plate secured to the center member and having its inner portion extending across the center member and constituting a beam for positively engaging the inner end of the coupler shank and limiting movement of the coupler relative to said center member in one direction.

27. In a car structure of the type embodying a draft member extending substantially the length of the structure and adapted for movement of large extent relative to the body bolster of said structure, a coupler connected to one end of said draft member and adapted for limited movement relative thereto, and resilient means mounted closely adjacent the coupler for resiliently resisting both relative movement of the draft member and movement of the coupler relative to said draft member.

28. A railway car structure including a bolster, a center member extending through said bolster and mounted for movement relative thereto, coupler means operatively connected with said center member for limited movement relative thereto to provide train slack, and means including two concentric and coextensive springs both extending from a point adjacent the inner end of the coupler shank of said coupler means to a recess in said bolster for yieldingly resisting said relative movement between said center member and bolster, the latter movement being of greater extent than the train slack provided by the coupler means.

29. In a railway car structure comprising a plurality of transverse members including a bolster, a center member extending substantially the length of the structure and mounted for movement relative to said bolster, resilient means for resisting said relative movement, and means for rendering said resilient means effective in both directions, said last named means including lugs and a standard type coupler secured to the center member, said resilient means extending between said lugs and the inner end of said coupler and operatively engaging said lugs at one of its ends and said coupler at its other end.

In testimony whereof I have signed this specification.

OTHO C. DURYEA.
